SAMUEL A. CONNER

By

Fred W. Hauck

ATTORNEY.

UNITED STATES PATENT OFFICE.

SAMUEL A. CONNER, OF UPLAND, CALIFORNIA.

SANITARY FOUNTAIN.

Application filed May 18, 1927. Serial No. 192,224.

This invention relates to drinking fountains for poultry.

One momentous problem confronting the poultryman is to keep his flock in good health.

5 To maintain a healthy flock it is required that sanitary conditions prevail. The ordinary drinking fountain provided for poultry consists of a single-rimmed container which is filled with water. The chickens roost on this single rim and contaminate the water, thus making it unsanitary.

10 It is an object of this invention to provide a drinking fountain in which the poultry will not roost on the fountain. The water in the fountain will not become contaminated and consequently sanitary conditions will prevail.

15 A further object of the invention is to provide a drinking fountain of this character in which the water will be kept cool even during the warm summer months.

20 Other objects and advantages of the invention will be made evident hereinafter.

Referring to the drawing in which my invention is illustrated:

25 Fig. 1 is a cross sectional view in perspective showing one form of this invention.

Fig. 2 is an enlarged fragmentary section of Fig. 1, this view being taken substantially as indicated by the line 2—2 of Fig. 1, this view being taken in the direction of the arrows.

30 Fig. 3 is a fragmentary section of an alternative form of the invention.

35 Referring particularly to Figs. 1 and 2, a pit 11 is dug in the ground, and placed in the pit 11 is a support-member 12 of the invention. Surrounding the support-member 12 are rocks or gravel 13 which provide cooling spaces. The support-member 12 is cylindrical, as shown, and is made of vitrified clay. The upper end of the support-member 12 projects above the surface of the ground and provides an outer rim 14 which surrounds an upper mouth 15. At the lower part of the outer rim 14 is an annular shoulder 17. At the surface of the ground and surrounding the support-member 12 is a platform 18, which is preferably made of cement. 40 In practice I place a ring 19 at the surface of the ground around the upper end of the support-member 12 and then fill in the interior of the ring with concrete, thus forming the platform 18. Adapted to be supported at the upper end of the support-mem-

ber 12 is the receptacle 21 of the invention. This receptacle 21 is in the form of a bowl and has an annular face 22 adapted to rest on the annular shoulder 17 of the support-member 12. In this manner the receptacle 60 21 is supported. The upper part of the receptacle 21 is in the form of an inner rim 23 and is spaced a short distance away from the outer rim 14 so as to provide an annular space 24. At intervals around the receptacle 21 are depressions 26. These depressions terminate above and below the shoulder 17 and the face 22 as illustrated clearly in Fig. 2. The purpose of the depressions 26 is to provide shoulders which may be engaged by a person extending his hands into the annular space 24 and his fingers into the depressions 26, so that the receptacle 21 may be removed from the upper end of the support-member 12; and to connect the annular space 24 with the interior of the support-member 12 below the shoulder 17.

70 Water is supplied to the receptacle 21 by means of a faucet 27. The faucet is opened so that water drips into the receptacle very slowly. This water will overflow the inner rim 23 of the receptacle and into the space 24. The overflowing water may pass from the space 24 through the depressions 26 to the lower part of the support-member 12.

75 The lower part of the support-member 12 may be left open where a drain means may be provided in the form of a conical bottom 30 having a central drain-tube 31. The overflowing water will seep downward through 80 the stones 13 and into the ground. The evaporation of the water and the dampness caused tends to keep the space between the stones, filled with cool air. This cool air keeps the interior of the support-member 12 85 and the water in the receptacle 21 comparatively cool so that the water will be in good condition for the chickens to drink.

90 One of the important features of the invention, as pointed out heretofore, is that chickens will not roost on the rim of the vessel. I have found that by providing a double rim, namely, the inner and outer rims 23 and 14 separated by the annular space 24, the chickens will not roost thereon. I cannot state 100 positively just why they do not, but I believe it is because of the fact that they do not like to extend their toes around both of the rims 23 and 14. The annular space 24 is 105 of such a size that the chickens cannot 110

veniently extend their toes around it and cannot conveniently extend their toes around only one of the rims. The chickens in drinking from the vessel of this invention will stand on the platform 18 and there will, therefore, be no possibility of the water in the receptacle 21 being contaminated.

In Fig. 3 I show an alternative form of the invention which is provided for the use of baby chicks. In this invention a receptacle of the form indicated by the numeral 40 is provided, this receptacle being much shallower than the receptacle 21 of the form of the invention shown in Figs. 1 and 2. Supported in the center of the receptacle 40 is a dome 41 which forms an annular channel 42 in the receptacle. The annular channel 42 is of such a size that the chicks cannot fall into it. It will be seen, therefore, that the primary purpose of the dome 41 is to prevent the chicks from falling into the receptacle.

The water is dripped into the receptacle 40 in the same manner as in the previous form of the invention and flows through the annular space 24 into the lower end of the support-member 12 in the same manner as in the first form of the invention.

The form of the invention illustrated in the drawing is adapted for outside use. When the invention is used inside, the drain-pipe 31 may be connected to the sewer.

I claim as my invention:

1. In a drinking vessel of the class described, the combination of: a support-member, said support-member being adapted to be placed in a hole in the ground and having a mouth at the upper end thereof, said mouth providing an outer rim, there being a shoulder at the lower end of said mouth; and a receptacle supported in said support-member, said receptacle having a face adapted to engage said shoulder whereby said receptacle is supported, an inner rim resting inside said outer rim and being separated therefrom by an annular space, and depressions formed in the outer surface of said re-

ceptacle, said depressions being formed so as to extend above and below said face.

2. In a drinking fountain of the class described, the combination of: a support-member having a shoulder thereon; an outer rim on said support-member; a receptacle in said support-member, said receptacle having a face adapted to engage said shoulder; an inner rim extending from said receptacle, there being an annular space between said rims; and means permitting a passage of water past said face and said shoulder.

3. In a drinking fountain of the class described, the combination of: a support-member having a shoulder thereon; a receptacle having a face engaging said shoulder and supported thereby, said receptacle having depressions adjacent said shoulder; an inner rim on said receptacle; and an outer rim on said support-member, said rims being relatively spaced so as to provide an annular space therebetween.

4. A combination as defined in claim 3 in which said depressions extend above and below said face, said depressions permitting a passage of water between said shoulder and said face.

5. In a drinking fountain of the class described, the combination of: a clay-support-member adapted to extend a distance in the ground and having its lower portion communicating with a drain; a porous body of loose particles positioned between said clay-support-member and the walls of the hole in which said support-member rests; a platform for closing said hole and extending around said support-member; a receptacle in said support-member; and means for supplying water to said receptacle, said water overflowing and passing downward between said receptacle and said support-member and reaching said porous body.

In testimony whereof, I have hereunto set my hand at Los Angeles, California, this 9th day of May, 1927.

SAMUEL A. CONNER.
